UNITED STATES PATENT OFFICE

140,556

DESIGN FOR A COMBINED CONTROL HANDLE AND HOOD FOR WATER VALVES

Jacques Stanitz, Warren, Ohio, assignor to Mullins Manufacturing Corporation, Salem, Ohio, a corporation of New York

Application December 28, 1944, Serial No. 117,114

Term of patent 7 years

(Cl. D91—1)

To all whom it may concern:

Be it known that I, Jacques Stanitz, a citizen of the United States, residing at Warren, in the county of Trumbull and State of Ohio, have invented a new, original, and ornamental Design for a Combined Control Handle and Hood for Water Valves, of which the following is a specification, reference being had to the accompanying drawing, forming part thereof.

Figure 1 is a perspective view of a combined control handle and hood for water valves showing my new design; and Fig. 2 is a side view thereof.

I claim:

The ornamental design for a combined control handle and hood for water valves, substantially as shown.

JACQUES STANITZ.
